UNITED STATES PATENT OFFICE.

ELMER B. WILBUR AND CHARLES B. WILBUR, OF SHENANDOAH, IOWA.

TYPE-WRITER ATTACHMENT.

1,200,558.

Specification of Letters Patent. Patented Oct. 10, 1916.

Application filed February 2, 1915. Serial No. 5,788.

To all whom it may concern:

Be it known that we, ELMER B. WILBUR and CHARLES B. WILBUR, citizens of the United States of America, residing at Shenandoah, in the county of Page and State of Iowa, have invented certain new and useful Improvements in Type-Writer Attachments, of which the following is a specification, reference being had therein to the accompanying drawing.

This invention relates to typewriting machines and has special reference to an electrically operated typewriting machine, wherein the type-bars may be actuated by means of an electrical apparatus, thereby facilitating the operation of the machine without the necessity of considerable force to the typewriter keys.

Another object of this invention is the production of a simple and efficient means for closing the electric circuit by means of the typewriting keys, whereby the type-bars may be efficiently operated.

With these and other objects in view this invention consists of certain novel combinations, constructions, and arrangements of parts as will be hereinafter fully described and claimed.

In the accompanying drawings:—Fig. 1 is a vertical section through the machine, the carriage and operating mechanism merely being indicated for the purpose of conveniently showing the operation of the device. Fig. 2 is a top plan view of the keyboard of the machine. Fig. 3 is a section taken on line 3—3, of Fig. 2. Fig. 4 is a horizontal section taken on line 4—4, of Fig. 1. Fig. 5 is a detail perspective of several of the type-bar actuating apertures. Fig. 6 is a perspective view of the electro-magnet supporting mechanism. Fig. 7 is an enlarged section taken on line 7—7, of Fig. 4. Fig. 8 is a detail perspective of the type-bar actuating mechanism. Fig. 9 is a detail perspective of one of the keys and contacts therefor. Fig. 10 is an enlarged section taken on line 10—10, of Fig. 3. Fig. 11 is a detail perspective of one of the key retaining brackets or yokes.

By referring to the drawings it will be seen that 1 designates the body of the machine which supports the usual platen 2, which platen is actuated in the usual or any convenient manner to suit the convenience of the manufacturer of the typewriting machine. A type-bar supporting shaft 3

is supported upon the frame of the machine, and upon this shaft 3 are pivotally supported the type-bars 4, which bars are of the usual construction and are provided with depending arms 5 for engaging the operating links 6. These links 6 are connected to one of the apertures 7 formed in the depending arm 5 of the type-bar 4 as clearly illustrated in detail in Fig. 8 by 60 having its bifurcated end secured thereto by means of a pin 8. The rear end of each link 6 is connected to an armature 9. A plurality of these armatures 9 are supported upon a shaft 10 extending transversely of the machine, and each armature 9 is provided with an armature plate 11, which plate is adapted to be attracted by means of the cores 12 of the electro-magnets 13 to be hereinafter more fully described. A plurality of coil springs 14 are mounted upon the shaft 10 and have their free ends engaging the armatures 9 for normally holding the same out of engagement with the electro-magnets 13 when 65 said electro-magnets are deenergized. The shaft 10 is supported upon a plurality of supporting brackets 15 as illustrated in detail in Fig. 5.

As above stated and as clearly illustrated in Figs. 1 and 6, the electro-magnets 13 which may be arranged in any suitable or desired manner are supported upon the spaced supporting rails 16 in a convenient manner to operate the respective armatures 9 carried by the shaft 10. Of course, it should be understood that each key and type-bar is operated by means of a separate magnet, and each type-bar 2 is also actuated by means of a separate armature 95 coöperating with its respective magnet. These rails 16 are secured to the base of the machine by means of the laterally bent ears 17.

A series of batteries 18 are supported 100 upon the base of the machine 1 and are connected to the respective magnets 13 by means of the wires 19 as clearly illustrated in Fig. 1. A wire 20 also leads from the batteries 18 and is connected to the respective contacts 21 carried by the bridges 22.

A supporting frame 23 of insulating material is carried by the front of the base 1 and is provided with a plurality of step portions 24 as clearly illustrated in Fig. 1 110 of the drawings. These step portions 24 are provided with a plurality of contact mem-

bers 25 which are connected to the respective magnets 13 by means of the conducting wires 26 as clearly illustrated in Fig. 1 of the drawings.

5 A spring metal or resilient key 27 is connected to each of the contact points 25 and carries an indicating knob 28 at the outer end thereof, which knob may have printed thereon the letter which is adapted to be 10 printed by means of the type-bar co-operating therewith. Of course, the letter may be removed from the knobs 28 if so desired when the machine is used for the touch 15 system.

15 The bridge portions 22 of insulating material which support the contact members 21 are so arranged as to allow the spring keys 27 to readily form a contact with the contact portions 21 supported thereby. Each 20 bridge portion 22 is provided with a plurality of spaced yokes 29 which are securely mounted upon the bridge portions 22 and straddle the spring keys 27 so as to limit the upward movement thereof, and also hold 25 the keys against material lateral swinging movement. These yokes 29 are provided with a cushioning covering 30 so as to act as a resilient buffer for the keys. The inner end of each key 29 is fixedly secured to a 30 contact point 25 as previously described and as clearly illustrated in Fig. 1.

By carefully considering Figs. 7 and 10 the construction of the yokes 29 will be clearly understood as well as the construction 35 of the contact members 21. Each contact member 21 is provided with an enlarged contact head 31 having a depending shank to which is secured a thumb nut 32 for the purpose of facilitating the connection 40 of the conducting wires 20 thereto.

It should be understood as will be obvious from the above description that the circuit may be closed through the magnets for energizing the same by the slightest pressure 45 upon the spring keys 27, whereby the electrical contact will be closed and thereby facilitate the energization of the magnets 13. It should be understood that the magnets are connected up to the batteries and to 50 the special contact points in such a manner as to cause the proper magnet to operate

the proper armature 9 and in turn actuate the proper type-bar which is adapted to co-operate with the key which has been operated.

55

As stated above, it should be understood that any suitable or convenient carriage mechanism may be employed in connection with the present invention without departing from the spirit of the invention, for the 60 principal object of the invention resides in the operating of the type-bar by means of the mechanism illustrated and described.

Of course, it should be understood that the device may be modified in its detail 65 mechanical construction without departing from the spirit of the invention.

Having thus described the invention what is claimed as new, is:—

An electrically operated typewriting machine comprising a base, a supporting frame 70 formed of insulating material carried by said base, a carriage supporting frame carried by said base, type-bars, electro-magnetic means for actuating said type-bars, 75 said insulated supporting frame comprising a plurality of ledge portions, a plurality of spring keys secured to said ledge portions, means for connecting said spring keys with said electro-magnetic means, finger engaging knobs carried by the outer ends of said keys, contact supporting bridges carried by said base and positioned in advance of said insulated frame, contact points carried by said contact supporting bridges, means for 80 electrically connecting said contacts with said electro-magnetic means, a plurality of yokes carried by said bridges and overhanging said keys for limiting the upward movement thereof and also holding said 85 keys against material lateral swing, and a cushion covering passing around said yokes for constituting a yieldable buffer for said keys.

In testimony whereof we hereunto affix 90 our signatures in presence of two witnesses.

ELMER B. WILBUR.
CHARLES B. WILBUR.
